UNITED STATES PATENT OFFICE

2,456,878

TIMBERMAN'S JACK

Helen G. Krupka and Joseph Jack Krupka,
Fairmont, W. Va.

Application January 31, 1945, Serial No. 575,442

9 Claims. (Cl. 254—85)

1

This invention herein described has reference to mine timbering and has for its primary object to provide a mechanical timberman by means of which roof supporting timbers may be easily, quickly and safely handled by one or two men, thus disposing of the necessity of having a large crew of timbermen for doing the roof propping work as has been necessary heretofore.

Another object of our invention is to provide a standard gauge mine car with means whereby heavy timber may be easily handled, transported and placed into position by one or two operators or timbermen.

Another object of our invention is to provide a relatively light mine car with a rotatably mounted jack and means whereby the car may be lifted upon or off of a track and carried to a desired place by a couple of men.

A further object of our invention is to provide in a mine car means for transporting heavy timbers, means for horizontally lifting the same, means for fitting the timber (that is, sawing the timber to a proper length) and means whereby the timber may be exactly placed into proper position.

A still further object of our invention is to provide in a mine car a timber supporting, rotatable jack having means for securely binding a timber to the jack head, and means whereby the timber may be fitted into position, that is shortened, while upon the raised jack and in approximate position.

Another object of our invention is to provide a mine car with a turn-table supported jack having a common roof-range lifting height together with means whereby such range may be increased for unusual height range.

Other features and advantages will become more readily apparent from the following description and the accompanying illustrative drawings in which:

Figure 1 is a side elevational view of my invention.

Figure 2 is a top plan view thereof.

Figure 3 is a detail elevational section of a jack head.

Figure 4 is an end view thereof.

Figure 5 is a detail section of a ratchet device.

Figure 6 is a detail sectional elevation of a turn-table.

Figure 7 is a top plan view of the turn-table.

Figure 8 is a sectional view taken on line 8—8 of Figure 1.

Figure 9 is a vertical section of part of a jack.

Figure 10 is a similar view of the lower portion of the jack.

Figure 11 is a detail elevational view of a clamping device.

Figure 12 is a detail of a horse member, and

Figure 13 is a detail of a jack section.

2

In the various views in the drawings and in the following specification, like reference characters indicate like parts throughout and the character 15, represents my invention as an entirety. The character 16, refers to a common type of mine car which has been fitted with my mechanical timberman. The car is provided with fore and aft handle bars 17, 18, 19 and 20, by means of which the car may readily be lifted bodily from one position to another and on or off of a track. Besides the usual platform 21, of the car, we provide an additional, spaced-apart platform 22. We also provide upon the platform 22, a pair of spaced-apart horse members 23 and 24, having V-cuts 25 and 26, in their upper ends 27 and 28, which align with one another and which are adapted to receive and hold a mine timber (not shown) and in order to securely bind the timber to said horse members there is provided a clamping device 29, comprising a pair of upright screws 30 and 31, secured to the opposite sides 32 and 33, of a block 34, and slidably upon these screws is a bowed clamp jaw 35, the horizontal ends 36 and 37, of which are provided with apertures through which the screws project. After a timber has been placed upon the said horse members the jaw 35 is placed in position and dropped down upon the timber, then clamped tightly thereupon by the nuts 38 and 39, the teeth 40, projecting from the lower surface of member 35, biting into the timber whereby it will be securely held to be sawed to a desired length by a portable electric saw 41, operated by a motor 42, mounted on the car 16.

Seated upon the platform 21, of the car 16, is a turntable 43, mounted upon castor wheels 44. The turntable is preferably in the form of a casting having inclined arms 45, projecting inwardly to a collar 46, through which a threaded tube 47, projects and is held in position by means of set screws 48. The lower end 49, of the tube 47, extends down through the platform 21, and also through a still lower spaced timber 50, secured to the under part of car 16. Seated in the end 49, of the tube 47, is a block 51, held by a pin 52, passing through a timber 53, and held by a pin 54. By means of the spaced-apart platform 22, platform 21, timbers 50, 53, and the collar 46, the tube 47, is held securely and rigidly in vertical position.

Operating through the tube 47, is a tubular lifting column 54, the lower end 55, of which is screw threaded, through the internally threaded operating nut or collar 56, rotatably seated upon the upper end 57, of the tube 47. Bosses 58 and 59, project up from the upper surface 60, of the member 56, and to these bosses are pivoted the right-angular inner ends 61 and 62, of the hand levers 63 and 64, by means of which the mem-

ber 56, may be rotated to screw up or down the column 54.

Removably mounted upon the upper end 65, of the said member 54, by means of a collar 66, is a jack head 67, in the form of a trough, adapted to receive a timber. The bottom wall arms 68, of the said head is provided at each end 69 and 70, thereof with bearings 71 and 72, 73 and 74, for supporting the respective spindles 75 and 76, of the rollers 77 and 78, which rollers are provided with centrally disposed aligning grooves 79 and 80. The roller 78, is provided throughout its peripheral surface 81, with spikes 82, for biting into a timber in order to move the same horizontally when the said rollers are rotated by means of the crank 83, on the projecting end 84, of shaft 76. Fixed on said end 84, is sprocket wheel 85, connected by a sprocket chain 86, to a sprocket wheel 87, on the end 88, of the shaft 75, of roller 77, whereby both rollers are simultaneously turned in order to shift a timber in one direction or the other. The side walls 89 and 90 of the jack head are adapted to secure a timber seated on the head, from accidental displacement (one of these walls has been removed from Figure 2 of the drawings in order to clarify the showing).

In case the column 54, should not be of a length to reach a desired position on the mine roof, there is provided extension column members 91, the upper portion 92, of which is of the same diameter as column 54, but the lower portion 93, is of sufficiently smaller diameter to fit snugly into said member 54, thus forming a seat 94, against which the upper terminal of 54 abuts. The member 91, may be of any desired length and any number of which may be used to build up said column 54, to a desired height.

The end 84 of shaft 76 is provided with a peripheral ratchet 95 over which is seated the barrel end 97 of crank 83 and in which end is provided a transverse slot 97' transversely of which is a pin 98 upon which is pivotally mounted the double pawl 96, either arm 99 or 100 of which may be engaged with the teeth 101 of said ratchet 95 by means of which the shaft 76 and its roller 78 may be rotated in one direction or another through the action of the crank 83. A spring 102, engageable with the detent 103, of the member 96, is adapted to hold the same in neutral position.

It is obvious from the foregoing description and explanation of the purpose and use of the various elements of our invention that a timber may be first seated upon the members 23 and 24, bound thereon to be sawed to exact length when accurately ascertained, then when the jack head is lowered, the timber may be seated thereupon, the jack secured against rotation by projecting any suitable timber through one of the openings 47, between arms 45, and against block 34, or in any other suitable manner, the car moved to approximate position, the crank 83, turned to bring the timber into exact position and then the jack again raised to adjust the timber into exact final position for securing.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details and parts such as come within the purview of the invention claimed may be resorted to, in actual practice, if desired.

Having now described our invention that which we claim as new and desire to procure by Letters Patent is:

1. A mine car, a pair of spaced-apart platforms thereon, a turn-table mounted on one platform and projecting through the other platform and a jack supported by the turn-table, said jack comprising telescopically connected tubes, one of which is screw-threaded and a threaded collar seated upon the other tube for operating the threaded tube, levers connected to the collar by means of which it is turned, a trough head for said threaded tube, rollers carried by said head for supporting a timber, means for turning said rollers, one of said rollers being spiked to bite into the timber.

2. A mine car, a pair of spaced-apart platforms thereon, a turn-table mounted on one platform and projecting through the other platform and a jack supported by the turn-table, said jack comprising telescopically connected tubes, one of which is screw-threaded, and a threaded collar seated upon the other tube for operating the threaded tube, levers connected to the collar by means of which it is turned, a trough head for said threaded tube, rollers carried by said head for supporting a timber, chain means for synchronously turning said rollers, means on a selected roller for biting into timber.

3. A mine car, a pair of spaced-apart platforms thereon, a turn-table mounted on one platform and projecting through the other platform and a jack supported by the turn-table, said jack comprising telescopically connected tubes, one of which is screw-threaded, and a threaded collar seated upon the other tube for operating the threaded tube, levers connected to the collar by means of which it is turned, a trough head for said threaded tube, rollers carried by said head for supporting a timber, means for turning said rollers, and one of said rollers being spiked to bite into the timber.

4. A mine car, a pair of spaced-apart platforms thereon, a turn-table mounted on one platform and projecting through the other platform and a jack supported by the turn-table, said jack comprising telescopically connected tubes, one of which is screw-threaded, and a threaded collar seated upon the other tube for operating the threaded tube, levers connected to the collar by means of which it is turned, a trough head for said threaded tube, rollers carried by said head for supporting a timber, and means for turning said rollers.

5. A mine car, a pair of spaced-apart platforms thereon, a turn-table mounted on one platform and projecting through the other platform and a jack supported by the turn-table, said jack comprising telescopically connected tubes, one of which is screw-threaded, and a threaded collar seated upon the other tube for operating the threaded tube, levers connected to the collar by means of which it is turned, a trough head for said threaded tube, and rollers carried by said head for supporting a timber one of the rollers being spiked.

6. A mine car, a pair of spaced-apart platforms thereon, a turn-table mounted on one platform and projecting through the other platform and a jack supported by the turn-table, said jack comprising telescopically connected tubes, one of which is screw-threaded, and a threaded collar seated upon the other tube for operating the threaded tube, lever means connected to the collar for turning said collar, a head on said threaded

tube, means for guiding lumber on said head and means for urging lumber through said guide means.

7. A mine car, a pair of spaced-apart platforms thereon, a turn-table mounted on one platform and projecting through the other platform and a jack supported by the turn-table, said jack comprising telescopically connected tubes, one of which is screw threaded, and a threaded collar seated upon the other tube for operating the 10 threaded tube, and means connected to the collar for turning said collar, a head on said threaded tube, means for urging lumber through said head, said last mentioned means including rollers, and means for synchronously actuating said rollers.

8. A mine car, a pair of spaced-apart platforms thereon, a turn-table mounted on one platform and projecting through the other platform and a jack supported by the turn-table, said jack comprising telescopically connected tubes, one of which is screw threaded and a threaded collar seated upon the other tube for operating the threaded tube, a head received on said screw threaded tube, rollers on said head and means for rotating said rollers.

9. The described device comprising a platform, a turn-table operable centrally of the platform, a jack supported upon the turn-table, a head on the jack, spaced rollers on the head, and means for synchronously rotating the rollers, one of which is spiked.

HELEN G. KRUPKA.
